CLAIM

The ornamental design for the valve cover, as shown and described.

DESCRIPTION

FIG. 1 is a perspective view of the valve cover embodying the new design;

FIG. 2 is an enlarged right elevational view thereof, the left elevational view being a mirror image thereof;

FIG. 3 is a front elevational view thereof;

FIG. 4 is a rear elevational view thereof; and,

FIG. 5 is a top plan view thereof.

The broken line shown in the drawings are for the purpose of illustrating portions of the article that form no part of the claimed design.
